UNITED STATES PATENT OFFICE

2,642,267

APPARATUS FOR INITIATING AND DRILLING DEVIATING CURVED BORES FROM EXISTING VERTICAL WELL BORES

John A. Zublin, Los Angeles, Calif.

Application January 17, 1951, Serial No. 206,364

2 Claims. (Cl. 255—1.6)

1

The present invention relates to an apparatus for initiating and drilling lateral curved bores deviating from an existing vertical well bore.

More particularly, it is an object and purpose of the present invention to provide an apparatus which is particularly efficacious in the drilling of lateral bores deviating from existing well bores in hard formations such as limestone and like hard formations.

More specifically, it is an object and purpose of the present invention to provide an apparatus which constitutes an improvement on an apparatus heretofore developed by me, such, for example, as disclosed and claimed in my United States Patent 2,382,933. The prior apparatus developed by me has great value and is particularly well suited for use in drilling in relatively soft formations. However, limestone formations which are formed in nature as a solid block are difficult to penetrate and the improvements presented by the present invention render the drilling of deviating bores in such formations economical and practical.

In its more specific aspects the present invention contemplates pressing a drilling bit sidewardly into the wall of an existing well bore with energy furnished by reaction of an elongated normally curved resilient flexible drill guide forcibly flexed to a lesser curvature within the existing well bore and in augmenting the force with which the bit is pressed sidewardly into the wall of the existing well bore by the deflecting forces imposed on the bit as the resilient drill guide is lowered over the inclined surface of a whipstock inserted in the well bore in advance of the normally curved flexible resilient drill guide.

Further and more detailed objects and advantages of the invention will become apparent as the description proceeds, which will be given by reference to the accompanying drawings, wherein

Figure 1 is a side elevation of one form of apparatus showing parts broken away for clarity.

Figure 2 is a front elevation of the lower portion of the embodiment of Figure 1.

Figure 3 is a plan view taken on line 3—3 of Figure 2.

Figure 4 is a cross-sectional view along the line 4—4 of Figure 2.

Figure 5 is a side elevation with parts shown in section of a second embodiment of an apparatus conforming to the present invention.

Figure 6 is a front elevational view of the lower portion of the embodiment shown in Figure 5.

Figure 7 is a transverse sectional view on the line 7—7 of Figure 5 taken in the direction of the arrows.

2

Figure 8 is a side elevation with parts shown in section of a third embodiment of apparatus corresponding to the present invention.

Figure 9 is a transverse sectional view on the line 9—9 of Figure 8 taken in the direction of the arrows.

Figure 10 is a side elevational view with parts shown in section of a fourth embodiment of apparatus conforming to the invention.

Figure 11 is a detailed cross-sectional view of the apparatus of Figure 10 showing the position assumed by the various elements of the apparatus during initiating of the drilling of a deviating bore.

Figure 12 is a transverse sectional view on the line 12—12 of Figure 10 taken in the direction of the arrows.

Figure 13 is a transverse sectional view on the line 13—13 of Figure 10 taken in the direction of the arrows.

Referring to the embodiment of the invention illustrated in Figures 1 to 4, the combination apparatus shown in Figure 1 is adapted to be carried in its entirety at the lower end of a substantially rigid drill string such as indicated at 10 in Figure 8, which substantially rigid drill string extends to the surface of the well and is adapted to be driven through a conventional rotary drilling mechanism. The combination of the embodiment of

Figure 1 embraces the flexible non-resilient drill string section 11, the upper end of which is broken away in Figure 1 but which it will be understood is connected to the rigid drill string in the same manner that the flexible non-resilient drill string section bearing the same reference numeral 11 in Figure 8 is illustrated in that figure as connected to the normally rigid drill string 10.

The flexible non-resilient drill string section 11 may preferably take the form of the non-resilient flexible drill pipe more particularly disclosed in my prior United States Patent 2,615,366 issued on July 18, 1950. It will be appreciated that, depending upon the length of the deviating bore desired to be drilled, one or more non-resilient flexible drill pipe sections 11 may be employed in the apparatus.

Below the flexible non-resilient drill string section 11 there is positioned the normally curved flexible resilient drill guide 12. It will be understood that the normal unstressed curved configuration of the drill guide 12 is such as to cause the same to be flexed to a substantially lesser curvature on insertion into an existing well bore to thereby store energy in said drill guide effective to force the bit 13 carried at the lower end of the

drill guide 12 sidewardly against the wall of an existing vertical well bore.

The flexible non-resilient drill string section 11 in reduced form as indicated at 11a in Figure 5 extends downwardly through the interior of the hollow normally curved flexible resilient drill guide 12 and the reduced portion 11a of the flexible non-resilient drill string section 11 constitutes the rotating means for driving the drill bit 13 to which it is connected at its lower end. Both the flexible non-resilient drill string section 11 and the reduced extension 11a thereof are made up of small independent units interconnected by dovetailed slots in the manner more specifically described in my United States Patent 2,515,366 hereinabove referred to. The normally curved flexible resilient drill guide 12 is preferably of the type disclosed in my United States Patent 2,515,365 issued July 18, 1950. This normally curved flexible resilient drill guide is formed of tubular metal pipe having a slot through the wall thereof extending in a generally helical path along and around the pipe. The sides of the slot are provided with intermeshing and interlocking dovetailed teeth. By way of illustration it is advantageous to employ a normally curved flexible resilient drill guide 12 which has an over-all length of about 16 feet and a curvature in its unstressed condition that lies on a radius of about 16 feet. Under such conditions the height of the arc formed by the guide when in unstressed condition will be found to be about 30 inches. When such a drill guide is inserted into a well bore, depending somewhat on the diameter of the well bore, the lower end of the drill guide will be forced against the side wall of the vertical bore in the absence of the augmenting force provided by the whipstock under a pressure of the order of from 100 to 700 pounds.

The specific manner in which the reduced portion 11a of the flexible non-resilient rotating drill string section 11 is mounted for rotation within the outer normally curved flexible resilient drill guide 12 is illustrated in greater detail in my copending application Serial No. 189,591 filed October 11, 1950, now Patent 2,585,207.

In the embodiment of the invention shown in Figures 1-4, the lower end of the normally curved flexible resilient drill guide 12 extends through the casing-like collar 14 at the upper end of the whipstock member indicated generally at 15. The opening 16 through the casing-like collar 14 is preferably in this embodiment slightly inclined from the vertical axis extending through the whipstock member 15 and the opening 16 is of a diameter only slightly greater than the diameter of the normally curved flexible resilient drill guide 12. The arrangement is such that the bit 13 positioned below the casing-like collar 14 will not pass through the opening 16. Thus the entire whipstock member 15 is suspended from the drill string and may be lowered into and withdrawn from the well with the drill string. The lower end of the whipstock member 15 carries the fishtail bit-like member 17 and the length of the intermediate coupling 18 will determine the elevation from the bottom of the well at which the inclined face 19 of the whipstock member 15 will be positioned. It will be appreciated that when the drill string is lowered into the well it can be oriented to insure the drilling of a deviating bore such as indicated at 20 in Figure 1 in any desired azimuth and the fishtail bit-like member 17 when it strikes the bottom of the vertical bore will act to hold the whipstock 75 shown in Figure 5 will be wholly adequate to

member 15 in such desired oriented position. The screw 21 is employed to interlock the lower end of a normally curved flexible resilient drill guide 12 and the casing-like collar 14 so as to hold the bit 13 substantially wholly within the confines of the outer circumference of the casing-like collar 14. The arrangement is such that the teeth of the cones 22 of the bit 13 are held out of contact with the walls of the well bore 23 as the apparatus is inserted into an existing well bore thereby avoiding wear on the teeth and unwanted gouging against the side wall of the existing vertical well bore. When the fishtail-like bit member 17 carried at the lower end of the whipstock member 15 strikes the bottom of the existing vertical well bore, the release at the surface of the well of the weight of the drill string shears the pin 21 which allows the normally curved flexible resilient drill guide 12 to be lowered through the opening 16 in the casing-like collar 14 and to advance over the inclined surface 19 of the whipstock member 15. It will be observed that the bit 13 carrying the cones 22 is thus forced against the side wall of the well bore 13 by the energy stored in the normally curved flexible resilient drill guide 12 which has been forcibly flexed to a lesser curvature by insertion into the well bore which is augmented by the wedging forces created through the advancement of the drill guide 12 over the inclined face 19 of the whipstock member 15. It will be appreciated that the release of weight of the drill string at the surface of the well will insure the creation of very substantial augmenting forces as the drill guide 12 moves over the inclined surface 19 tending to force penetration of the formation by the driven bit 13.

The several embodiments of the invention have in common the feature of augmenting the lateral directing force imparted to the bit by the energy stored in the normally curved flexible resilient drill guide 12 through passage of the latter under controlled pressure over the inclined surface of an associated whipstock.

Referring to the embodiment of Figure 5, it will be observed that the flexible non-resilient drill string section 11a is of substantially lesser diameter than the normally curved flexible resilient drill guide 12 so that the flexible non-resilient drill string section 11a can extend downwardly completely through drill guide 12 as indicated in dotted lines and be connected at its lower end to the drill bit 13a. In this embodiment there is provided an elongated casing or sleeve 24 carrying a collar 25 at its upper end. The opening 26 in the collar 25 has a diameter only slightly greater than the diameter of the flexible non-resilient drill string section 11a and thus considerably less than the outside diameter of the drill guide 12. The arrangement is such that the upper end of the drill guide 12 abuts the shoulder 27 of the collar 25 and prevents upward withdrawal of the drill guide 12 through the collar 25. The sleeve 24 is substantially longer than the over-all length of the drill guide 12 and the bit 13a so that the sleeve 24 completely encases the guide 12 and bit 13a during insertion of the apparatus into an existing vertical well bore. It will be appreciated that the friction developed between the casing 24 and the normally curved flexible resilient drill guide 12 created by forcibly flexing the drill guide 12 from its normally curved configuration to the straight configuration occupied thereby in the position shown in Figure 5 will be wholly adequate to

hold the elements of the apparatus in the relationship shown in Figure 5 during the insertion of the apparatus into an existing well bore. It will be further observed that the bit 13a carrying cones 22a is housed within the hollow casing 24 during insertion of the apparatus in the vertical well bore so that contact of the teeth of the cones with the wall of the vertical well bore is completely avoided.

A portion of the wall of the casing 24 near the bottom thereof is cut away as indicated at 28 to provide a window through which the bit 13a, the drill guide 12 and the flexible non-resilient drill string section 11a may be projected. Opposite the window provided by the cut-out portion 28 is disposed the inclined surface 29 of the whipstock member 30 welded as indicated at 31 to the casing 24. The whipstock member 30 is connected through coupling 32 with the fishtail-like bit member 33 which functions in altogether a similar manner to the functioning of the fishtail-like bit member 17 of the embodiment of Figure 1. Rib-like members 34, 35 and 36 are welded to the outer wall of the casing 24 (see Figure 7) and serve the two-fold purpose of acting as sled runner-like members during the insertion of the apparatus into an existing well bore and further act in conjunction with the fishtail-like bit member 33 in holding the apparatus in a desired position of orientation during the drilling of a deviating bore.

In the embodiment exemplified by Figures 5-7 no shear pin is required. The entire combination is insertable into and withdrawable from a well bore as a unit. In this embodiment when the fishtail-like bit member 33 strikes the bottom of the existing well bore, the release of weight on the drill string at the surface of the well will be sufficient to force the normally curved flexible resilient drill guide 12 carrying the bit 13 down through the upper closed portion of the casing 24 and over the inclined surface 29 of the whipstock member 30. As soon as the normally curved flexible resilient drill guide 12 begins to emerge through the window provided by the cut-out portion 28, the energy stored therein due to its having been flexed to a lesser curvature is released and effected to force the bit 13a against the side wall of the existing well bore and the force thus applied to the bit is augmented by the wedging action occasioned through passage of the drill guide 12 downwardly over the inclined surface 29 of the whipstock. The embodiments of Figures 5-7 have some advantages over certain other embodiments herein disclosed in that no elongating strain is placed on the normally curved flexible resilient drill guide 12 in withdrawing the apparatus from the well bore which of course is not the case with the more simplified embodiment of Figure 1 which has, however the advantage of being more economically produced.

The embodiment of Figure 8 presents a variant of the embodiment of Figure 5 in that in Figure 8 the casing 24a is provided with a much larger cut-out portion 28a than is the case in 24 of Figure 5. Thus in the embodiment of Figure 8 the normally curved flexible resilient drill guide 12 is held in interlocked relationship with the casing 24a by the shear pin 37, the arrangement being such that the drill bit 13b is held wholly within the confines of the circumference of the casing 24a when the apparatus is inserted into an existing vertical well bore. When the fishtail-like bit member 38 strikes the bottom

of the existing vertical bore, the pin 37 is sheared off by the weight of the drill string and the bit 13 together with the drill guide 12 then pass downwardly over the inclined face 39 of the whipstock member 40 with the result that the lateral force upon the bit 13b represents the energy stored in the drill guide 12 as augmented by the wedging force incident to passing the same over the inclined surface 39 of the whipstock 40. When the apparatus of the embodiment of Figure 8 is withdrawn from the well, the coupling member 41 carries laterally extending ribs 42 which engage the shoulder 43 of the collar 25a at the upper end of the casing 24a. Thus, in this embodiment no longitudinal strain is imposed on either the flexible non-resilient drill string section 11 or the drill guide 12 during withdrawal of the apparatus from the well since the coupling 41 is directly connected to the lower end of the substantially rigid drill string 10.

Referring to the embodiment illustrated in Figures 10-13 inclusive, it will be observed that this embodiment is primarily intended for the drilling of relatively sharp deviating bores from a vertical well bore, that is, deviating bores of no greater length than the length of the normally curved flexible resilient drill guide 12. It will be understood that in this embodiment an inner flexible non-resilient drill string section of smaller diameter than the drill guide 12 extends down through the drill guide 12 for driving the drill bit 13c. The upper end of the inner flexible non-resilient drill string member is connected through the tubular rigid coupling 44 to the lower end of the substantially rigid drill string 10. The rigid tubular coupling 44 is provided with the annular shoulder 45 for a purpose which will be presently described. The casing 24b in this embodiment is provided with an extended cut-out portion 28b and with a collar 25b at the upper end of the casing. A shear pin 46 is employed to interlock the normally curved flexible resilient drill guide 12 and the casing 24b during the lowering of the apparatus into an oil well. In this embodiment the whipstock member 47 is free to partake of relative longitudinal movement with respect to the casing 24b. The lower end of the casing 24b is provided with a tubular collar 48 having a keyway 49 extending along one side of the tubular opening 50. An elongated coupling member 51 interconnects the whipstock member 47 and the fishtail-like bit member 52. The elongated member 51 is provided with a key 53 which moves through the keyway 49 in the collar 48 and prevents relative rotation of the whipstock member 47 with respect to the casing 44b. The member 51 is of a length substantially equal to the over-all length of the casing 24b. When the fishtail-like bit member 52 strikes the bottom of the vertical well bore due to the fact that coupling 44 can move down through the tubular collar 25b for a distance equal to the space between the top of the collar 25b and the shoulder 45, the shear pin 46 will be sheared off by the limited downward movement of the drill guide 12 with respect to the casing 24b. When the shoulder 45 or tubular coupling 44 strikes the top of the collar 25b no further relative longitudinal movement between the drill guide 12 and the casing 24b will occur. However, the casing 24b is free to move downwardly around the whipstock member 47 and downward pressure by weight of the drill string through shoulder 45 on the top of the

collar 25b will force the casing 24b downwardly over the whipstock 47 and cause the latter to move into a position between the flexible drill guide 12 and the casing 24 as more particularly shown in Figure 11. As the casing 24b and the drill guide 12 move downwardly with respect to the whipstock 47, the bit 13c is forced laterally into the formation by the energy stored in the drill guide 12 as augmented by the passing thereof over the inclined surface 54 of the whipstock 47. In this embodiment when the apparatus is withdrawn from the well, the upper end of the drill guide 12 strikes the lower face of the collar 25b and thus there is no longitudinal strain on the drill guide 12 during withdrawal of the apparatus from the well.

From the foregoing it will be appreciated that the basic method of the present invention is susceptible of being practiced by any one of numerous apparatus embodiments. In all instances the laterally directing force applied to the bit represents the energy stored in a normally curved flexible resilient drill guide which has been forcibly flexed to a lesser curvature as augmented by the additional forces developed through passage of the drill guide under pressure downwardly over an inclined surface of a whipstock, through which medium lateral deviating bores may be effectively drilled in hard formations of the character of limestone and the like.

Having thus described my invention, what I claim is:

1. An apparatus adapted to be carried in its entirety at the lower end of a rotary drill string for drilling curved bores deviating from an existing well bore, comprising in combination a rotatable flexible drill string section made up of a plurality of units so interconnected as to permit of limited relative angular movement of adjacent units in all directions, a normally curved metallic flexible resilient drill guide surrounding at least a portion of said flexible drill string section said guide having a slot in the wall thereof extending in a generally helical path around and along said guide, the upper end of said flexible drill string section being connectable to the lower end of the rotary drill string, a drill bit carried at the lower end of said flexible drill string section for rotation therewith, an elongated sleeve surrounding at least a portion of said rotatable flexible drill string section and said flexible resilient drill guide and insertable

therewith into an existing well bore, a whipstock having an exposed camming face secured at the lower end of said sleeve said normally curved flexible resilient drill guide being effective to exert pressure on the bit in the same direction as that of the wedging action of said whipstock whereby upon relative vertical movement of said bit and said whipstock the bit is forced sidewardly, by the wedging action of said whipstock, and the action of said normally curved flexible resilient drill guide against the wall of the existing bore to initiate and thereafter drill a deviating bore.

2. An apparatus adapted to be carried in its entirety at the lower end of a rotary drill string for drilling curved bores deviating from an existing well bore comprising, in combination, a rotatable flexible drill string section made up of a plurality of units capable of limited relative angular movement in all directions; a sub having a laterally extending shoulder carried at the upper end of said flexible drill string section, the upper end of said sub being connectable to the lower end of a rotary drill string; a drill bit carried at the lower end of said flexible drill section; an elongated rigid sleeve substantially entirely surrounding, within the confines of its circumference, said flexible drill section, sub and bit during insertion of said apparatus into an existing well bore; a collar carried at the upper end of said sleeve for engagement with said shoulder of said sub when said flexible drill string section is raised to permit withdrawal of said apparatus as a unit from a well bore; and a whipstock having an exposed camming face carried at the lower end of said sleeve.
